BUILDING FRONT

James A. Salmans, 511 N. Broadway,
New Philadelphia, Ohio 44663

Filed Oct. 28, 1969, Ser. No. 19,759

Term of patent 14 years

Int. Cl. D25—U.S. Cl. D13—1

FIG. 1

FIG. 1 is a front elevation view of a building front showing my new design; and

FIG. 2 is a side elevation view;

FIG. 3 is a side elevation view thereof in section taken on line 3—3 of FIG. 1 looking in the direction of the arrows.

I claim:

The ornamental design for a building front, as shown.
